UNITED STATES PATENT OFFICE

HAROLD W. HOLMES, OF DETROIT, MICHIGAN, ASSIGNOR, BY MESNE ASSIGNMENTS, TO CINCINNATI GRINDERS INCORPORATED, OF CINCINNATI, OHIO, A CORPORATION OF OHIO

TRUING DEVICE

Application filed August 14, 1928. Serial No. 129,184.

This invention relates to grinding machines and more particularly to devices for truing or shaping the surface of the abrasive wheel or wheels in grinding machines.

5 It is an object of the present invention to provide a grinding machine having a truing device which is of simple construction and may be efficiently operated and yet which is positioned upon the grinding machine so 10 as not to be in the way of the operator during the grinding operation.

Another object of the invention is to provide a truing mechanism which is simple to operate and by means of which the abrasive 15 wheel may be quickly and accurately dressed or trued. Other objects will be in part obvious or in part pointed out hereinafter.

The invention accordingly consists in the features of construction, combinations of elements, and arrangements of parts as will be exemplified in the structure to be hereinafter described and the scope of the application of which will be indicated in the following claims.

25 In the accompanying drawing in which is shown one of the various possible embodiments of this invention,

Fig. 1 is a side elevational view partly in section of a portion of a grinding machine 30 embodying the invention;

Fig. 2 is a front elevational view of the same;

Fig. 3 is a sectional detail view taken substantially as indicated by the line 3-3 in 35 Figure 2 of the adjustable mounting for the forming bar shown in Figs. 1 and 2; and

Fig. 4 is a sectional view taken along the line 4-4 of Fig. 2.

The machine shown in the drawing includes a grinding wheel 10 mounted upon a spindle held in suitable bearings upon the main frame (not shown) of the machine. A guard 11 is mounted upon the frame of the machine so as to extend around a portion of

40 the wheel and is provided with a pair of pads 12 and 13 having flat surfaces for supporting parts of the truing mechanism. A bracket 14 is secured upon the pad 12 by screws 15 and is provided with a pair of upwardly ex- 45 tending arms 16 and 17 each of which is pro-

vided with a bearing 18 for supporting a hollow cylindrical supporting member 19 which is adapted to turn freely therein.

An arm 20 is provided with bearings 21 and 22 which slidably embrace the supporting member 19 and the arm 20 is constructed relatively heavy and is provided with a weight 25 so that the follower 26 (Figure 1), which is mounted in the arm 20, may be held with considerable force against the guiding 55 surface of a forming bar 27. One end of the bar is mounted to turn about a shaft 28 in a bracket 29 held upon the pad 13 by screws 30. The bracket 29 is provided with a cylindrical hole 31 adapted to receive for slidably 60 engagement therewith a cylindrical block 32 provided with a flat inclined surface 33 (Fig. 3).

The block 32 is provided with a screw 34 extending from one end thereof and adapted 70 to engage a knob 35 which rests against a shoulder 36 on the bracket 29 and is held thereagainst by a U-shaped washer 37 fitting in a groove 38 in the knob and secured to the bracket 29 by screws 39. The hole 31 is 75 provided with an opening 40 to permit the bearing 41 projecting from the free end of the forming bar 27 to engage the inclined surface 33 upon the cylindrical block 32. An inclined surface 42 (Figure 4) is provided 80 upon the forming bar 27 near its free end and upon the side opposite the cylindrical block 32. The bearing 41 upon the forming bar is held in a desired position against the inclined surface 33 upon the block 32 by a 85 cone pointed screw 43 passing through the bracket 29 and engaging the inclined surface 42 to hold the forming bar against swinging 90 outwardly. The knob 35 is provided with graduations 44 (Figure 2) so that the guiding surface 45 of the forming bar may be accurately adjusted in a desired angular position relative to the axis of the abrasive wheel.

The lower end of the arm 20 is provided 95 with a cylindrical portion 47 having a hole 48 to receive a cylindrical slide 49 which is slidably mounted therein and held against rotative movement by a dog point screw 50 in the cylindrical portion 47 and adapted to 100

engage a groove 51 in the slide 49. A holder 52 carrying a dresser 53 is threaded into the end of the slide 49. The other end of the slide 49 is provided with a hole 55 into which a nut 56 is forced to make a tight fit therewith. The nut 56 is adapted to receive a screw 57 provided with a bearing surface 58 for mounting in a bearing bushing 59 which is secured to the cylindrical portion 47 by a screw 60. A collar 61 is formed as an integral part of the screw 57 and is adapted to engage the bushing 59 to prevent axial movement of the screw 57. A star shaped knob 63 is mounted upon the screw 57 and is prevented from turning relative thereto by a key 64 secured in the screw 57 and adapted to engage a groove 65 in the knob 63, and is held against the end of the bearing 59 by a nut 66 upon the end of the screw. A scale 67 is provided upon the knob 63 cooperating with an index mark at 68 on the bearing 59 so as to insure accurate adjustment of the dresser 53 relative to the abrasive wheel 10 in a direction toward and away from the axis thereof.

25 The arm 20 is moved upon the cylindrical support 19 (Figure 2) in the direction of the axis thereof by a screw 70 adapted to engage a nut 71 within the supporting member 19, the supporting member 19 being held against turning relative to the arm 20 by a pin 72 passing through the bearing 22, through the wall of the hollow cylindrical member 19 and engaging the nut 71. A slot 73 is provided in the supporting member 19 to provide a free passageway for the pin 72 as the arm 20 is moved axially of its cylindrical support 19. The screw 70 is mounted for rotation within a bearing bushing 74 provided with a shoulder 75 adapted to engage a collar 76, which engages the end of the member 19 and one of the bearings 18 and is secured to the latter by any suitable means. A collar 78 integral with the screw 70 is adapted to engage the end of the bearing 74 to prevent axial movement of the screw. The bearing 74 is held against movement relative to the slide 19 by a screw 79 passing through the slide and engaging the bearing. A hand wheel 81 having a handle 82 is mounted upon the screw 70 by a key 83 in the screw engaging a slot 84 in the wheel. The wheel 81 is held against the bushing 74 by a nut 85 secured upon the screw 70 and engaging the hub 86 of the wheel.

55 The annular plate or collar 76, the shoulder 78 on the screw shaft 70, the bushing 74 and the screw 79 hold the cylindrical supporting member 19 against axial movement in the bearing supports 16 and 17 and hold the screw shaft 70 against axial movement. When the hand wheel 81 is rotated, the nut 71 is moved lengthwise of the hollow support 19 and, due to the connecting pin 72, the arm 20 moves therewith in a direction transversely of the operative surface of the abrasive wheel 10 or

substantially axially of the wheel to carry the dressing tool 53 across the wheel surface.

Considering now the operation of this truing mechanism, if it is desired to dress the wheel 10 so that its operative surface is parallel to its axis, the forming bar 27 is first adjusted so that its surface 45 is parallel to the wheel axis. This is accomplished by turning the thumb nut 35 (Figure 2), the scale 44 indicating the adjustment, and the set screw 43 being first released if necessary. When the screw 43 is tightened down against the surface 42 of the forming bar it locks the forming bar in the position to which it is adjusted.

The forming bar having been properly adjusted in position, the hand wheel 63 is now operated to move the dressing tool 53 toward or away from the wheel surface, as may be required in order to take a proper cut, the slide 49 moving to shift the position of the tool 43 relative to the arm 20 when the hand wheel 63 is turned. These adjustments having been made, the hand wheel 81 is now turned and this feeds the dressing tool across the wheel surface to dress the wheel accurately to shape. If it is desired to dress the wheel to a tapered form, this is accomplished by first adjusting the position of the forming bar 27 so that its operative surface 45 is out of parallelism with the axis of the wheel, the forming bar being angularly adjustable with respect to the wheel axis by operating the thumb nut 35 to swing the forming bar around its end pivot 28.

As many possible embodiments may be made of the above invention and as many changes might be made in the embodiment above set forth, it is to be understood that all matter hereinbefore set forth or shown in the accompanying drawing is to be interpreted as illustrative and not in a limiting sense.

Having thus described my invention, what I claim as new and desire to secure by Letters Patent is:

1. A grinding machine comprising a grinding wheel, a guard around the wheel, a truing mechanism mounted upon the guard including a cylindrical support, an arm slidably mounted on and arranged to turn about the axis of the support, a dresser adjustably carried upon the opposite end of the arm and arranged to be pressed against the wheel by the action of gravity, means for limiting the movement of the dresser toward the wheel under the urge of gravity, means for adjusting the position of the dresser relative to said arm towards and from the wheel, and means for causing the dresser to move across the periphery of the wheel along a line substantially parallel to the axis of the wheel.

2. A grinding machine comprising a grinding wheel, a guard around the wheel, a truing mechanism mounted upon the guard includ-

- ing an arm slidably and pivotally secured thereto, a dresser mounted upon the arm so as to permit movement toward the wheel for engagement therewith, means for sliding the 5 arm relative to the wheel to cause the dresser to move across the periphery of the wheel along a line substantially parallel to the axis of the wheel, and a forming bar mounted upon the guard and adapted to guide the movement of the dresser across the wheel. 10
3. A grinding machine comprising a grinding wheel, a guard around the wheel, a truing mechanism mounted upon the guard including an arm slidably and pivotally secured 15 thereto, a dresser mounted upon the arm so as to permit movement towards the wheel for engagement therewith, means for moving the arm to cause the dresser to move across the periphery of the wheel along a line substantially parallel to the axis of the wheel, a 20 forming bar adjustably mounted upon the guard to guide the movement of the dresser across the wheel, and means for adjusting the position of the forming bar relative to 25 the axis of the wheel.
4. In apparatus for truing an abrasive wheel, in combination, a depending supporting arm mounted for movement in a direction substantially axially of the wheel and 30 pivoted to swing toward and away from the wheel surface about an axis adjacent its upper end, a dressing tool mounted in said arm adjacent its lower end in a position to move into and out of engagement with the wheel 35 surface as said arm swings about its said axis, means for limiting the swinging of said arm, and means for moving said arm to move said tool across the wheel surface. 40
5. In apparatus for truing an abrasive wheel, in combination, a supporting arm mounted for movement in a direction substantially parallel to the axis of the wheel, a dressing tool on said arm adapted to engage the wheel surface, said arm being pivotally 45 mounted to swing toward and away from the wheel surface and being urged by gravity to swing toward the wheel surface, means for limiting the swinging movement of said arm by gravity, and means for moving said arm 50 to move said tool across the wheel surface.
6. In apparatus for truing an abrasive wheel, in combination, a supporting arm mounted for movement in a direction substantially parallel to the axis of the wheel, 55 a dressing tool on said arm adapted to engage the wheel surface, said arm being pivotally mounted to swing toward and away from the wheel surface and tending to swing toward the wheel surface to hold said tool 60 in engagement therewith, means for moving said arm to move said tool across the wheel surface, and means for limiting the movement of said arm toward the wheel surface and for controlling the path of movement 65 of said tool. 125
7. In apparatus for truing an abrasive wheel, in combination, a supporting arm mounted for movement in a direction substantially parallel to the axis of the wheel, a dressing tool on said arm adapted to engage 70 the wheel surface, said arm being pivotally mounted to swing toward and away from the wheel surface and tending to swing toward the wheel surface to hold said tool in engagement therewith, means for moving said arm to move said tool across the wheel surface, and a forming bar adjustable in position with 75 respect to the wheel axis adapted to limit the movement of said arm toward the wheel surface and to control the path of movement of said tool. 80
8. In apparatus for truing an abrasive wheel, in combination, a supporting arm mounted for movement in a direction substantially parallel to the axis of the wheel, a dressing tool on said arm adapted to engage 85 the wheel surface, said arm being pivotally mounted to swing toward and away from the wheel surface and tending to swing toward the wheel surface to hold said tool in engagement therewith, means for moving said arm to move said tool across the wheel surface, means for limiting the movement of said arm toward the wheel surface, and means for adjusting the position of said tool 90 relative to said arm in a direction toward and away from the wheel surface. 95
9. A grinding machine, comprising a grinding wheel, a cylindrical support mounted adjacent said wheel, a truing mechanism including an arm slidably and pivotally mounted on said support, a dresser carried by said arm adapted to move across the wheel surface when said arm slides, the center of gravity 100 of said arm being so located in relation to the pivotal axis thereof as to urge said dresser into operative relation with said wheel by the action of gravity, adjustable means for limiting the movement of the dresser toward the wheel under the urge of gravity, means for sliding said arm along said support, and means for adjusting the position of the dresser relative to the arm in a direction toward and away from the wheel. 105
